UNITED STATES PATENT OFFICE.

WILLIAM SCOTT MORTON, OF EDINBURGH, COUNTY OF MID-LOTHIAN, SCOTLAND.

METHOD OF EMBOSsing CANVAS FOR DECORATING WALLS OR OTHER SURFACES.

SPECIFICATION forming part of Letters Patent No. 395,915, dated January 8, 1889.

Application filed February 15, 1887. Serial No. 227,458. (No model.) Patented in England November 18, 1884, No. 15,161, and December 2, 1885, No. 14,793; in France September 22, 1885, No. 171,281, and in Belgium September 23, 1885, No. 70,284.

To all whom it may concern:

Be it known that I, WILLIAM SCOTT MORTON, a subject of the Queen of Great Britain and Ireland, residing at Edinburgh, in the county of Mid-Lothian, Scotland, have invented an Improvement in the Methods of Embossing Canvas for Decorating Walls or other Surfaces, (for which I have obtained British patents dated November 18, 1884, No. 15,161, and dated December 2, 1885, No. 14,793; French patent dated September 22, 1885, No. 171,281, and Belgian patent dated September 23, 1885, No. 70,284,) of which the following is a specification.

This invention has for its object to improve and cheapen the manufacture of embossed canvas for decorative purposes, and in carrying it out there are provided molds for producing the raised ornamental devices on the canvas. These molds may consist of plates of metal or other suitable material formed by casting from patterns or otherwise and placed on a metal chest or casing, or the mold may be formed in the top plate of the metal chest. Instead of making the molds flat, they may take the form of a hollow metal cylinder. The molds are heated by means of steam or other hot fluid. The canvas is first prepared by boiling or steeping in boiling water, and subsequently steeping in hot size and wringing or squeezing out to a suitable extent. It is then applied to the molding-surfaces and worked into all the cavities of the mold by means of brushes or pads. A backing of pasted paper is then applied and the heat of the mold causes the canvas to rapidly stiffen and dry, so as to retain the embossed effect. The brushes or pads may be worked by hand or by apparatus of the kind described in the specification of the United States patent granted to the present applicant, No. 294,257, dated February 26, 1884.

Figure 1 of the accompanying drawings is a perspective elevation of my improved embossing machine as made with a flat mold-plate, Fig. 2 being a transverse section of the mold-plate and steam-chest, and Fig. 3 a transverse section of a modification of the mold-plate and steam-chest.

In the arrangement shown in Figs. 1 and 2 a plate, 8, of metal or other suitable material, is formed by casting from patterns or otherwise shaping it so as to serve for a mold for producing raised ornamental devices on the canvas, the design being *in intaglio* in the surface of the plate. This mold-plate 8 is placed on a shallow metal chest or casing, 9, to which it is secured by bolts. Branch pipes 10 enter the casing, and are connected to a central horizontal pipe, 11, fitted with a drip-cock, 12. This pipe 11 extends to one end of the apparatus and has connected to its outer end two horizontal transverse pipes, 13 14, fitted with stop-valves 15 16, the outer ends of the pipes 13 14 being connected to two vertical pipes, 17 18. Steam for heating the casing 9 enters by the pipe 17, its admission being regulated by the stop-valve 15, and water for cooling the casing enters by pipe 18, the stop-valve 16 regulating its admission. The mold-plate 8 is provided with cocks 19 for the escape of air, and is slightly inclined from the end at which the stop-valves 15 16 are placed toward a corner at the opposite end, where there is fitted a vertical discharge-pipe, 20, having at its lower end a drip-cock, 21. The discharge-pipe 20 is connected by a short horizontal pipe to two vertical pipes, 22 23, having stop-valves 24 25. The lower pipe, 22, and valve 24 are for the discharge of steam, while the upper pipe, 23, and valve 25 are for the discharge of water, and they extend sufficiently high to insure the chest 9 being completely filled with the cooling-liquid. The outer ends of the pipes 22 23 are connected to horizontal pipes 26, which communicate with a vertical discharge-pipe, 27.

Fig. 3 shows the chest 9 as made in one piece and the mold-plate 8 laid on the top of it.

When the canvas has been sized, as herein-before described, it is laid on the mold-plate and worked into all the cavities by brushes or beaters, the deeper cavities being packed with paper-pulp, papier-maché, or other suitable substance, and a paper-backing is pasted over the whole. After the moistened and sized canvas has been worked into the cavi-

ties, steam is admitted to the casing 9 by the pipe 17 and continued until the canvas has become quite dry, when it is removed from the plate 8. The steam is then discharged through the stop-valve 24, and the plate 8 is cooled by means of water admitted to the casing 9 by the pipe 18, and after acting therein it is discharged by the stop-valve 25.

It is necessary to have the molding-surface cool when the moistened and sized canvas is first laid on it; otherwise the canvas would become dry and set before it would be properly molded or worked into the intaglio surfaces.

5 I claim as my invention—

1. The mode herein described of making embossed decorative work, said mode consisting in sizing the canvas, then working it into the

intaglio parts of a mold, and afterward applying heat to the mold with the canvas 20 on it.

2. The mode herein described of making embossed decorative work, said mode consisting in sizing canvas, then working it into the intaglio parts of the mold, packing the deeper 25 parts of the embossed canvas with paper-pulp or similar material and applying heat to the mold, and pasting a paper backing over the whole.

In testimony whereof I have signed my name 30 to this specification in the presence of two subscribing witnesses.

WM. SCOTT MORTON.
